(57) **CLAIM**

The ornamental design for a handheld pain relief therapy instrument, as shown.

DESCRIPTION

FIG. 1 is a front view depicting a handheld pain relief therapy instrument;

FIG. 2 is a top view depicting the handheld pain relief therapy instrument;

FIG. 3 is a left side view depicting the handheld pain relief therapy instrument;

FIG. 4 is a right side view depicting the handheld pain relief therapy instrument;

FIG. 5 is a bottom view depicting the handheld pain relief therapy instrument;

FIG. 6 is a rear view depicting the handheld pain relief therapy instrument; and,

FIG. 7 is a front perspective view depicting the handheld pain relief therapy instrument.

The broken lines shown in the figures are for the purpose of illustrating portions of the handheld pain relief therapy instrument, which form no part of the claimed design.

1 Claim, 7 Drawing Sheets
